STEAM LOCOMOTIVE ENGINE

Otis W. Young, Winchendon, Mass., assignor of
one-half to Henry S. Mann and one-half to
Charles D. Young, both of Chicago, Ill.

Application August 30, 1937, Serial No. 161,577

7 Claims. (Cl. 105—37)

Among the principal objects of this invention are the following:

To provide a practical self balancing device for synchronizing the operation of the driving wheels on a locomotive, and

To provide such a device in which the problem of lubrication is reduced to a minimum, and one whose operating vibrations are considerably less than those of prior devices.

10 Other objects and advantages will become apparent as the disclosure proceeds and the description is read in conjunction with the accompanying drawings, in which

15 Fig. 1 is a side elevational view of a locomotive embodying the present invention;

Fig. 2 is a fragmentary plan view of the under-frame of the locomotive showing the manner in which the present invention is applied;

20 Fig. 3 is a more or less diagrammatic side elevational view of the locomotive embodying the present invention;

Fig. 4 is a longitudinal sectional view taken on the line 4—4 of Fig. 2;

25 Fig. 5 is a plan view of the crank axle shown in Fig. 2, and indicating the crank throw of a conventional crank axle;

Fig. 6 is a diagram indicating comparatively the crank throw of the conventional crank axle and that of the crank axle employed in the 30 present invention;

Fig. 7 is a diagrammatic view showing the maximum leverage of the combined side rods as well as the maximum leverage of the three throw connecting rods extending between the crank 35 axles;

Fig. 8 is a modified form of the crank axle;

Fig. 9 is a longitudinal section of the crank axle shown in Fig. 8;

40 Fig. 10 is an end view of the crank axle shown in Fig. 8;

Fig. 11 is a vertical sectional view of the modified form of crank axle taken on the line 11—11 of Fig. 9;

Fig. 12 is a vertical sectional view taken on the 45 line 12—12 of Fig. 9; and

Fig. 13 is a vertical sectional view taken on the line 13—13 of Fig. 9 and showing one of the three throw connecting rods assembled on the eccentric crank.

50 The particular embodiments of this invention are selected for the purpose of disclosure only and are not intended to limit the claims beyond what is required by the state of the prior art.

The demand of the traveling public for higher speeds has caused railroads to greatly reduce

their train schedules. To do this, it has been necessary for them to operate their trains at much higher running speeds and has caused them to attempt to cut down, wherever possible, losses of time due to station stops, grades, etc.

5 It is a well known fact that short spurts of extremely high speeds, interspersed with periods of low speeds and delays does not produce as high an average speed over a distance as does a maintained constant high speed, somewhat 10 lower in value than the extremely high speed, without delays.

This latter condition is impossible to attain with conventional steam trains because of the loss of time occasioned by station stops and the 15 material drop in running speeds due to grades.

Any attempt to overcome this difficulty present in steam trains, however, must be made with the remembrance that steam locomotives running at high speeds over the rails produce a terrific pounding action on the rails and road bed. Any increase in this pounding would be very detrimental and would undoubtedly make such a locomotive unfit for high speed service. The problem then is to increase the average running 20 speeds of the conventional locomotives in an efficient manner without increasing the vibrations at high speed.

The present invention accomplishes this result by materially increasing the tractive power of the 30 locomotive without otherwise altering the running qualities.

Referring now to the figures, a locomotive embodying the invention is shown in Fig. 1 and comprises a boiler 20 followed by the usual cab 35 21. Along the top of the locomotive are mounted the usual stack 22, steam dome 23 and sander 24, and at the front end is carried the pilot 25.

The locomotive is mounted on driving wheels 26, 27, 28 and 29, and at the front are pilot 40 31, while at the rear are trailing wheels 31.

The frame of the locomotive includes longitudinal members 32 and 33, one extending along each side of the frame. Cylinder castings 34 and 45 35 are secured to the frame in some suitable manner and are carried by the longitudinal members 32 and 33 respectively. Each of these castings is adapted to carry two steam cylinders, 40 and 41 respectively, Fig. 3, one above the other, and 50 in each cylinder is a piston 53, both operating in opposite directions. As shown, the upper piston on each side of the locomotive drives the forward pair of driving wheels, while the lower piston drives the rear pair of drivers.

Axes 36, 37, 38 and 39 are carried by the drivers and are journalled in the usual manner on the locomotive frame.

As shown in Figs. 2, 3 and 4, the power from the pistons 53 is transmitted through piston rods 42 and 43 respectively, to cross heads 44, which in turn drive main connecting rods 45 and 46, the latter being rotatively secured to the outside crank pins 47 and 48 respectively. Thus it is seen that the thrust of the pistons is transmitted directly to the driving wheels 26 and 29, which are furthest from the cylinders. The inner drivers, 27 and 28 receive their power from the driving wheels 26 and 29 by means of side rods 49 and 50 which are secured, one end to the outside crank pins 48 and 47, and the other ends of which are rotatively secured to the outside crank pins 51 and 52, respectively. These rods are mounted on their respective crank pins by means of yokes 55 in which the pins are journalled and which are fastened to the ends of the connecting rods in any suitable manner.

The outside crank pins and connecting rods are power transmitting elements and consequently must be of sufficient size and strength to withstand relatively large stresses. Also, for mechanical reasons, the throw of the crank pins should be equal to the piston stroke.

Axes 37 and 38 in the present instance are crank axles carrying three cranks 56, 57 and 58 positioned 120° apart, so as to insure perfectly balanced axles. Extending between these axles are three rods 59, 60 and 61 each being secured to one of the cranks 56, 57 or 58, in some suitable manner, as for example by yokes 62, secured to the ends of the rods by means of nuts 63.

It is the purpose in the present invention to segregate the driving wheels into two groups, the forward group consisting of drivers 26 and 27 and the rear group comprising drivers 28 and 29. All of the wheels in the forward group are coupled together by the side rods 49 so that they rotate in synchronous manner. Likewise the rear driving wheels are caused to operate together by means of the rods 50. The purpose of the inside rods 59, 60 and 61 is to couple together the forward and the rear group of wheels so that should one group commence to slip due to insufficient traction between the wheels and the rails, it would be prevented from doing so because of the resistance to slipping of the other group of wheels.

Under ordinary conditions, these inside rods 59, 60 and 61 are subject to practically no stresses, their function being merely to take up the forces caused by the difference in slippage between the two groups of wheels. These forces are relatively small in comparison with those imposed upon the outside rods 49 and 50, and consequently the throw of the cranks 56, 57 and 58 need be very small in proportion to the throw of the outside cranks 47 and 48 which is in direct proportion to the piston stroke.

The comparison of the throw of the conventional crank axle where only two cranks are used with the crank employed in the present invention may be had by referring to Figs. 5 and 6. In Fig. 5, vertical line A—B represents the extreme throw of the conventional crank axle, while the throw of the axle used in the present invention is the outside dimension of the crank axle. This comparison is impressive in the showing of the diagram, Fig. 6, in which the circles 65 and 66 respectively, represent the conventional cranks spaced 90 degrees apart and the outer circle 67 indicates the extreme throw of such a

crank axle. The inner circles 68, 69 and 70 indicate the relative positions of the crank axle in the present invention and the circle 71 indicates their extreme throw. This smaller crank very materially diminishes the vibrations of the locomotive while traveling at high speeds, thereby lowering the cost of track maintenance.

As indicated by the dotted lines 72 and 73 in Fig. 3 and by the showing in Fig. 7, the outside cranks 47 and 48 situated on one side of the locomotive are set at an angle of 90 degrees from the corresponding outside cranks operating on the other side of the locomotive. In the locomotive having a 24 inch cylinder stroke, the maximum leverage of the two side rods is 17 inches, as shown in Fig. 7, while the combined leverage of the three throw connections with only a 10 inch circle of the crank axle is 8½ inches. Furthermore, when using three rod connections instead of two, the difference between the maximum and minimum leverage is very much less.

The crank axle shown in Figs. 2 and 5 is the usual type of crank which may be machined from a solid forging. The modified form of axle, which may be termed a balanced eccentric axle, is shown in Figs. 8 through 13, and includes an axle shaft 74 extending the full length of the crank axle, an eccentric bearing casting or sleeve 75 provided with three crank bearings 76, 77 and 78 positioned 120 degrees apart, and two grease plugs 79.

Before the parts are assembled the axle shaft 74 has a central portion 80 extending between points C and D which has a uniform diameter throughout its length slightly greater than the diameter of the remainder of the shaft. Shoulders 99 on the axle 74 have a diameter no greater than that of the central portion 80 of the axle so that the sleeve 75 may be passed over the ends of the axle. At each end of the shaft wheel seats 81 are provided upon which the driving wheels are mounted, and between these seats and the enlarged central portion 80 are provided bearing portions 82 having a diameter slightly less than that of the wheel seats 81. It is at these bearing portions 82 that the crank axle is journalled.

A cylindrical passage 83 extends longitudinally through the axle shaft, having a uniform diameter between approximately the shoulders 99 of the wheel seats 81 but having a greater diameter through the seat portion as shown at 83. The passage opening in the end face of each axle is countersunk as shown at 84. These enlarged portions 89 of the passage are threaded as indicated at 85.

In assembling the parts of the eccentric crank axle the casting 75 is shrunk onto the enlarged central portion 80 of the axle shaft, and keyed in place by means of keys 86 fitted into suitable keyways cut into the axle shaft and the eccentric casting, and then if desired, the casting may be welded to the axle shaft as indicated at 87. The bearing surfaces of the eccentric cranks 76, 77 and 78 are then turned down, a portion of the axle shaft 74 being removed as indicated at 88. At no time, however, is the diameter of the eccentric bearings 76, 77 or 78 made less than the diameter of the journal bearings 82.

Inserted into the passage 83 through each of the enlarged ends 89 is a grease plug 79 having a long shank 91 and a head 92 secured to the end of the shank machine screw 93. The head 92 is provided with a longitudinal passage 94, the inner portion of which is adapted to receive the 75

shank of the screw 93, and the outer portion 95 of which has a diameter larger than the inner portion to permit passage of the head of the screw. The extreme outer portion of this passage 94 is in the shape of a square in section as shown in Fig. 10 at 96, to provide a bolt for receiving a wrench. A lock washer 97 having a similar square shaped slot is inserted into the passage after the grease plug has been admitted.

10 The surfaces of the crank bearings 76, 77 and 78 are in communication with the passage 83 by means of ports 98 extending radially from the passage so that grease which is stored in the passage 83 will pass to the bearing surfaces to provide proper lubrication.

I claim as my invention:

1. In a locomotive having a plurality of wheeled axles, at least two of which carry driving wheels, a separate source of locomotive power for each 20 pair of driving wheels, an eccentric bearing sleeve mounted on each of the last named axles, each sleeve cooperating with its corresponding axle to form an eccentric bearing with an eccentricity less than the diameter of the axle, and a connecting rod disposed between the two axles and journaled on the bearings.

2. In a locomotive having a plurality of wheeled axles, at least two of which carry driving wheels, a separate source of locomotive power for each 30 pair of driving wheels, an arcuate groove in each of the two axles between the opposite ends thereof extending circumferentially around the axle for a portion only of its circumference, an eccentric bearing sleeve comprising a pair of spaced collars 35 concentrically mounted on the axle, one on each side of the axle groove, and an arcuate bearing portion between the collars extending partially around the axle circumferentially and on the diametrically opposite side of the axle from the 40 groove, and a connecting rod extending between the said two axles and journaled on the eccentric bearings, the grooved portion of the axle and the bearing portion of the eccentric bearing sleeve together serving as the bearing for the connecting 45 rod.

3. In a steam locomotive supported on a plurality of wheeled axles, at least two of which carry driving wheels, two steam cylinders on each side of the locomotive, one of the corresponding 50 cylinders on each side driving one pair of driving wheels, the other of the corresponding cylinders driving the other pair of driving wheels, an eccentric bearing sleeve mounted on each of said last named axles, each sleeve cooperating with

its corresponding axle to form an eccentric bearing with an eccentricity less than the diameter of the axle, and a connecting rod between the said two axles and journaled on the bearings.

4. In a locomotive having a plurality of wheeled axles, at least two of which carry driving wheels, a separate source of locomotive power for each pair of driving wheels, an eccentric bearing sleeve mounted on each of the last named axles, each sleeve cooperating with its corresponding axle 10 to form an eccentric bearing with an eccentricity less than the diameter of the axle, and a connecting rod disposed between the two axles and journaled on the bearings, said sleeve being so arranged with respect to the axle that the axle 15 may be passed entirely through the sleeve.

5. In a steam locomotive supported on a plurality of wheeled axles, at least two of which carry driving wheels, two steam cylinders on each side of the locomotive, one of the corresponding 20 cylinders on each side driving one pair of driving wheels, the other of the corresponding cylinders driving the other pair of driving wheels, an eccentric bearing sleeve mounted on each of said last named axles, each sleeve cooperating with 25 its corresponding axle to form an eccentric bearing with an eccentricity less than the diameter of the axle, and a connecting rod between the said two axles and journaled on the bearings, each of said sleeves being arranged with respect to its 30 axle so that it may be passed over the end of the axle and fitted into place.

6. In a locomotive supported on a plurality of wheeled axles, at least two of which carry driving wheels, a separate source of locomotive power for 35 each pair of driving wheels, a bearing sleeve mounted on each of said two axles, each sleeve cooperating with its corresponding axle to form an eccentric bearing with an eccentricity less than the diameter of the axle, and a connecting 40 rod between the two axles and journaled on the eccentric bearings, said sleeve being so arranged with respect to the axle that the axle may be passed entirely through the sleeve.

7. In a locomotive supported on a plurality 45 of wheeled axles, at least two of which carry driving wheels, a separate source of locomotive power for each pair of driving wheels, an eccentric bearing sleeve mounted on each of said two axles, said sleeve being removable from the axle, 50 and a connecting rod between the two axles and journaled on the eccentric bearings.

OTIS W. YOUNG.
